DESIGN FOR A TIRE

Albert E. Caldwell, Newark, N. J., assignor to
Atlas Supply Company, Newark, N. J.

Application August 11, 1934, Serial No. 52,929

Term of patent 7 years

To all whom it may concern:

Be it known that I, Albert E. Caldwell, a citizen of the United States, residing at Newark, in the county of Essex and State of New Jersey, have invented a new, original, and ornamental Design for Tires, of which the following is a specification, reference being had to the accompanying drawing, forming part thereof.

Figure 1 is a fragmentary perspective view of a tire, only a section thereof being in full lines, showing my new design. Figure 2 is a sectional view taken on the line II-II of Figure 3, and Figure 3 is a view in plan.

I claim:

The ornamental design for a tire, as shown.

ALBERT E. CALDWELL.
